UNITED STATES PATENT OFFICE

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY

LOCKSTITCH SEWING MACHINE

Application filed May 14, 1928. Serial No. 277,619.

The invention relates to lockstitch sewing machines and is herein disclosed as embodied in a lockstitch horn shoe sewing machine of the McKay type.

5 The object of the invention is to provide a novel and improved mechanism for supplying needle thread for the stitch forming operation which has a new and simple mode of operation and acts efficiently and certainly 10 to set the stitch a uniform distance into the work.

With this object in view, one feature of the invention consists in the provision of mechanism which acts to pull the needle loop yieldingly into contact with the surface of the work, and then to draw thread sufficient in amount for the next stitch from the supply, and finally to draw the loop into the surface of the work a predetermined distance so that 20 a regular even stitch is obtained with the stich set a uniform distance into the work.

Another feature of the invention consists in the provision of a thread handling mechanism having a mode of operation substantially as above described which is particularly adapted for use in a lockstitch horn shoe sewing machine of the type herein disclosed as embodying the present invention.

The several features of the invention consist also in the devices, combinations and arrangement of parts hereinafter described and claimed, which together with the advantages to be obtained thereby, will be readily understood by one skilled in the art from the following description taken in connection with the accompanying drawings.

In the drawings, Fig. 1 is a view in side elevation of a lockstitch horn shoe sewing machine embodying the present invention; Fig. 2 is a view in front elevation of the head of the machine with parts broken away to illustrate particularly the shuttle and needle and associated parts; Fig. 3 is a detail view in front elevation of the take-up and thread lock mechanisms for the needle thread; Fig. 4 is a detail view partly in section of the parts illustrated in Fig. 3; Figs. 5 and 6 are detail views of the two cooperating cam surfaces for operating the thread lock; and Figs. 7 to 10 inclusive are somewhat diagrammatical

views illustrating the positions of the thread handling mechanisms for four different steps in the cycle of operation.

The invention is illustrated as embodied in the lockstitch horn shoe sewing machine more fully described in the inventor's pending application Serial No. 169,203, filed February 18, 1927.

In carrying out the present invention, means are provided for drawing the old needle loop yieldingly down into contact with the work against a thread tension after which thread for the next stitch is drawn through the tension from the supply. Finally the loop is drawn down a predetermined amount by a mechanism which has a constant throw and acts positively against a thread lock so that the stitch is always set at a uniform distance into the work. In the illustrated construction, a take-up lever, situated directly beneath the base of the horn, acts against the thread lock to draw the loop from the shuttle partially down to the work leaving sufficient thread for one side of the needle loop on the next succeeding stitch. At this point the thread lock is removed and as the new loop is passed around the shuttle, the old loop is drawn yieldingly down to the work against a thread tension until the resistance offered by the contact of the loop with the work exceeds the amount of the tension when thread is drawn off from the supply for the formation of a new stitch. While thread is being drawn from the supply, the old needle loop rests on the surface of the work and in order to complete the stitch, it is merely necessary to pull the loop down a small amount which will be constant for each stitch regardless of the thickness of the work to set the loop a uniform distance into the work.

To accomplish this, in the present construction, the thread lock is closed at a predetermined point in the movement of the shuttle just before the loop which has been taken from the needle passes over the top of the shuttle so that the continued movement of the shuttle draws a certain fixed amount of thread from the preceding loop and pulls the loop into the work the required amount to secure an even regular seam.

Referring more specifically to the drawings, the machine column is indicated at 12 provided with a sewing head 14 in which are mounted the straight hook needle 16, the presser foot 18, the feed point 20, and the oscillating shuttle 22. The shuttle is actuated in timed relation to the needle through connections from the needle actuating mechanism which parts, together with the presser foot and feed point, are all driven from the horizontally situated sewing cam shaft 24 in the head of the machine which is in turn driven from the motor 26 in the base through the vertical shaft 28 and intermediate connections, as fully described and illustrated in the above-mentioned application.

A work supporting horn 30 is rotatably mounted on a support or base 32 secured to the machine column and is provided with a whirl 34 which is driven in timed relation to the sewing cam shaft and the instrumentalities mounted in the head through connections from the vertical drive shaft 28 which include the horizontal shaft 36, the intermeshing bevel gears 38 and 39, and the vertical shaft 40 which in turn drives the whirl actuating mechanism in the horn.

The thread handling elements of the machine include in addition to the parts already named, a thread tension 42 and a thread lock comprising the two clamping plates 44 and 46, and a take-up lever 48.

The take-up mechanism of the machine is located directly beneath the horn, and is actuated from the horizontal shaft 36 through which the whirl is driven by means of a crank pin 50 mounted on a cam disk 52 which is secured to the end of the shaft 36. The crank pin 50 is connected by a link 54 to the central pivot 56 of the toggle levers 58 and 60 which are connected respectively to the fixed pivot 62 and to one end of the take-up lever 48 which has a fixed pivot 64. In order to permit the throw of the take-up lever 48 to be regulated in accordance with the thickness of the work so that a sufficient amount of thread will be left in the old loop to supply one side of the new needle loop, the pivot 62 of the toggle lever 58, and the pivot 64 of the take-up lever are mounted on a bracket 66 which is pivotally mounted on a stud 68 fixed in the machine frame, and is secured to the stud by a binding bolt 70. An arm extending upwardly from the hub of the bracket and provided with a slot through which a set screw 72 extends into the frame affords additional means by which the bracket may be adjusted and retained in position to give the desired amount of throw to the take-up lever.

To further facilitate the handling of the needle thread, an auxiliary take-up is provided consisting of a lever 73 mounted on the take-up lever 48, provided with an eye 75 through which the thread is passed. A spring 77 stretched between the auxiliary

take-up lever and a point on the take-up lever 48 tends to turn the auxiliary take-up lever about its pivot to take up slack thread. The movement of the lever in the opposite direction is limited by the engagement of the flange 70 81 formed on the lower end of the lever with the under side of the take-up lever 48.

The thread clamp is actuated to release the thread during the earlier part of the movement of the shuttle to permit new thread to be drawn off from the supply and is then closed at a predetermined point in the movement of the shuttle to set the stitch a uniform distance into the work by means of mechanism which comprises a cam 74 on the cam disk 52 which is adapted to engage with a cam roll 76 on a cam lever 78 secured to one end of a shaft 80. The two clamping plates 44 and 46 comprising the thread lock are mounted on the shaft 80 and interposed between an abutment 82 on the machine frame and the hub of the cam lever 78. To the other end of the shaft is secured a cam faced block 84 which is held in engagement with an opposing stationary cam faced block 86 by means of a spring 88 coiled about the shaft between the cam block 84 and the machine frame. When the cam roll 76 rides on to the high portion of the cam 74, the shaft 80 is rocked and moved axially against the pressure of the spring 88 through the inter-connection of the cam faced blocks 84 and 86 to release the thread clamp, as illustrated in Figs. 3 and 4. When the cam roll reaches the low portion of the cam, the pressure of the spring 88 causes the shaft 80 to be rocked in the opposite direction by the contact of the cam blocks and the shaft to be moved axially to close the thread clamp.

The operation of the thread handling mechanism in forming a stitch is indicated somewhat diagrammatically in Figs. 7 to 10, inclusive. The needle loop is drawn down from the shuttle partially to the work by means of the take-up lever 48, enough thread being left in the old loop to provide thread for one side of the needle loop of the next succeeding stitch, as shown in Fig. 7. The thread lock at this time is closed to insure that the loop is drawn down through the work to the required extent from the shuttle. As the needle is retracted to draw the new needle loop through the work, the remaining thread from the old loop is drawn around through the work, and the thread required for the other side of the needle loop is given up by the retracting movement of the take-up. At this point in the operation illustrated in Fig. 8, the thread lock is open as the cam roll 76 rides on to the raised portion of the cam 74. As the loop is taken from the needle and carried around the shuttle, the old loop is drawn firmly down against the work until the resistance offered by the contact of the loop with the work exceeds the amount of the tension, and additional thread for the new loop is 130

drawn off from the supply. Finally, the thread lock is again actuated to clamp the thread at a predetermined point in the movement of the shuttle with the parts in the positions shown in Fig. 9 before it reaches the limit of its loop drawing stroke, so that the preceding loop is pulled down a predetermined amount against the thread lock to set the stitch a uniform distance into the work, 10 as illustrated in Fig. 10.

The nature and scope of the invention having been indicated, and one embodiment thereof in a lockstitch horn shoe sewing machine having been described, what is 15 claimed is:

1. A lockstitch sewing machine having, in combination, stitch forming and setting devices including a hook needle, a take-up for drawing a loop of needle thread partially 20 down to the work to leave sufficient thread for one side of the needle loop on the next succeeding stitch, a shuttle acting to draw off thread from the supply for the next stitch and thereafter to set the stitch, a thread lock 25 against which the stitch is set, and means for closing the thread lock at a predetermined point in the movement of the shuttle.

2. A lockstitch sewing machine having, in combination, stitch forming and setting devices including a hook needle, a thread tension, a take-up for drawing a loop of needle thread partially down to the work to permit the needle on the next succeeding stitch to draw thread for one side of the needle loop 35 from the preceding loop, a shuttle acting upon the new loop first to draw the old loop into contact with the work against the thread tension and thereafter to draw off thread from the supply for the next stitch, a thread 40 lock against which the stitch is set, and means for closing the thread lock at a predetermined point in the movement of the shuttle.

3. A lockstitch shoe sewing machine having, in combination, stitch forming and setting devices including a hook needle, a thread tension, means for drawing down the needle loop against the tension until the resistance offered by contact of the loop with the work exceeds the amount of the tension and for 45 thereafter drawing off thread through the tension from the supply for the next stitch, and a thread lock against which the stitch is set.

4. A lockstitch shoe sewing machine having, in combination, stitch forming and setting devices including a hook needle, a thread tension, means for drawing down the needle loop against the tension until the resistance 50 offered by contact of the loop with the work exceeds the amount of tension and for thereafter drawing off thread through the tension from the supply for the next stitch, a thread lock, and means for pulling down the 55 loop a predetermined amount against the

thread lock to set the stitch a uniform distance into the work.

5. A lockstitch sewing machine having, in combination, stitch forming and setting devices including a hook needle, a thread tension, a thread lock, a shuttle acting to pull on the preceding needle loop against the tension until the resistance offered by the loop exceeds the amount of tension, then to draw off thread through the tension from the supply for the next stitch and to finally set the stitch, and means for closing the thread lock at a predetermined point in the rotation of the shuttle after thread has been drawn from the supply for the next stitch to cause the stitch to be set during the continued rotation of the shuttle.

In testimony whereof I have signed my name to this specification.

BERNARD T. LEVEQUE.
